UNITED STATES PATENT OFFICE.

EDWIN O. ADAMS, OF SHELBY, MONTANA.

OIL-WELL-DRILLING RIG.

Application filed October 21, 1927. Serial No. 227,750.

This invention relates to new and useful improvements in oil well drilling rigs and aims to provide a unitary structure for use in performing the various operations incident to the drilling of a well such as the spudding in of the well, the placing of the well casing section, the drilling and bailing of the well. The invention further aims to provide a well drilling rig wherein the same as a unit may be jacked up and moved from one well to another within a particular oil field, and that furthermore may be entirely disassembled for repair, renewal, or transportation or storage purposes. Further, the location of the various structural elements with respect to the rig frame is such that all loads will be substantially centered with respect to the complete unit so that there will be no liability whatever of the rig bucking or tilting.

From the foregoing it will be apparent that the main object of this invention is to provide a unitary rig structure wherein the various operations necessary in the drilling of an oil well may be performed through the medium of the single mechanism.

With the foregoing and other objects in view as the nature of the invention will be better understood, the same comprises the novel form, combination and arrangement of parts hereinafter more fully described, shown in the accompanying drawings and claimed.

In the accompanying drawings wherein like references indicate corresponding parts throughout the several views:

Figure 1 is a fragmentary side elevation of my improved rig, the walking beam and its connection being removed from the power shaft and the power shaft equipped with means whereby the initial operation usually known as spudding in of the well may be performed.

Figure 2 is a somewhat similar fragmentary side elevation disclosing the rig as being employed to perform the bailing operation.

Figure 3 is a fragmentary side elevation disclosing the walking beam in position, and as operatively connected to the power shaft at one end and to the drilling tool line at its opposite end, in this instance the rig being employed to perform the usual drilling operation.

Figure 4 is a fragmentary horizontal section taken substantially upon the line 4-4 of Figure 3 for more clearly disclosing the

walking beam structure and the structure of the vertical mast at the particular point through which the forward end of the walking beam projects.

Figure 5 is a fragmentary elevation of the side of the rig opposite to that disclosed in Figures 1, 2 and 3 for more clearly disclosing the means whereby the bailer cable drum may be rotated or braked.

Figure 6 is a fragmentary front side perspective of the lower end of the rig mast.

Figure 7 is a fragmentary front elevation of the rig mast.

Figure 8 is a horizontal section through the rig mast and the walking beam Samson post at a point directly beneath the walking beam for disclosing the main power shaft and the various cable drums together with their associated elements in top plan.

Figure 9 is a fragmentary transverse section taken at a point directly in back of the walking beam Samson post for disclosing generally in side elevation a clutch mechanism that is provided for causing when desired the rotation of the drill tool cable drum so that the drill tools may be raised.

Figure 10 is an enlarged fragmentary perspective disclosing certain of the frame elements of the rig together with certain members of the clutch operating mechanism directly associated with said members.

Figure 11 is an enlarged transverse section taken through the main power shaft of the rig for disclosing mainly in side elevation and partially in cross section the particular clutch unit employed in association with this invention.

Figure 12 is a fragmentary perspective of a circular friction band that constitutes an essential element of the clutch mechanism, and that is rigidly associated with the power shaft bull wheel.

Figure 13 is an enlarged fragmentary section through the clutch mechanism.

Figure 14 is an enlarged fragmentary section through the upper end of the rig mast for more clearly disclosing one of the block and tackle cable guide pulley units, and

Figure 15 is a front elevation of the upper end of the mast for more clearly disclosing the positioning of these cable guide pulley units with respect to the rig mast.

Now having particular reference to the drawings, my novel rig consists of a horizontal bed frame consisting of outer longitudinally extending frame bars 5-5 and a pair of

spaced parallel central longitudinally extending frame bars 6—6. Extending transversely beneath these bars 5—5 and 6—6 and at predetermined spaced relation with each other are 5 transversely extending bars 7 that are of course rigidly secured to the longitudinally extending bars and serve to support the same above the ground surface as clearly disclosed in Figures 1, 2 and 3. Furthermore, this bed 10 frame consists of a transversely extending bar 8 arranged across the longitudinal bars 5 and 6, and bolted thereto, this bar 8 being disposed at a point adjacent one end of the bed frame as also disclosed in Figures 1, 2 and 3 as well 15 as in Figures 5 and 8. At the outer sides of the central longitudinally extending frame bars 6—6 the front side of the transverse bar 8 is equipped with hinge sections 9—9, while normally supported upon this transverse bar 20 8 is the lower end of an upwardly and slightly inclined mast structure 10 that includes generally side bars 11—11 of interconnected sectional formation the lower ends of the bottom sections being formed with forwardly extending 25 toes 12—12 for pivotal attachment to the hinge members 9—9 of the transverse bed frame bar 8 for the obvious purpose of permitting the mast to be swung downwardly whenever desired. 30 The side bars 11—11 of the mast structure 10 converge slightly inwardly toward their upper ends, while said side bars are braced at predetermined spaced points by horizontal strut bars 13 and diagonally extending struts 35 14. Adjacent the lower end of this mast 12 two adjacent horizontal struts 13 are interconnected by a pair of spaced guide members 15—15 as clearly disclosed in Figure 7. By a consideration of this view it will be noted that 40 the diagonal struts between the two horizontal struts carrying the vertical guides 15—15 are so arranged as not to cross the space between said vertical guides, the purpose of which is to permit the forward end of the walking beam, hereinafter described, to project therethrough and to have vertical movement therebetween. 45 The side members 11—11 of the mast 12 are equipped at points above their centers and adjacent their upper ends with rings or other suitable means 16 whereby forwardly and rearwardly extending guy wires 17 may be extended therefrom, the ends of these guy wires being obviously anchored to the ground 55 and serving to prevent rocking of the mast during operation of the rig.

Extending transversely between the side members 11—11 of the mast structure 10 adjacent the upper end thereof is a wall 18, while 60 extending vertically from this wall 18 intermediate the ends thereof is a pair of spaced parallel arms 19—19, upon the upper end of which is mounted for rotation a cable guide pulley 20. Beneath this pulley 20 there is 65 arranged between the arms 19—19 a small

cable guide pulley 21. Beneath the outer sides of the arms 19—19 and the upper ends of the side members of the mast structure are insert braces 22—22, while arranged within the spaces between the side members of the mast 70 structure and the arms 19—19 are sheave carriers designated generally by the reference characters 23—23. Each sheave carrier consists of three spaced parallel metallic plates 24 between the upper ends of which are cable sheaves designated in each instance by the reference characters 25—25. These sheave carriers are pivoted within the mentioned spaces of the mast structure adjacent their forward edges by a cross pin 26. The rear edges of the 80 plates comprising these sheave carriers are formed adjacent their upper ends with rearwardly extending somewhat arcuate shaped tongues 27 within each of which is an arcuate slot 28 through which a pin 29 extended transversely of the mast structure is arranged. Obviously, this pin and slot arrangement regulates the degree of swinging movement of the sheave carriers with respect to the mast structure, as clearly disclosed in Figure 14. 85 Secured at their lower ends to the bed frame of the rig directly in back of the transversely extending mast supporting bar 8 is a double standard Samson post 30, the standards of which are in spaced parallel relation 90 and that are braced adjacent their upper ends by downwardly and rearwardly extending brace rods 31 connected at their lower ends to the inner sides of the central longitudinally extending bed frame bars 6—6. Furthermore, the standards of this Samson post 100 are braced to the side members of the mast structure 10 by suitable straps 32. The upper ends of the standards of this Samson post are equipped with shaft bearings 33—33 for 105 receiving the opposite ends of a rock shaft 34 that is suitably attached to the top surface and intermediate the ends of a walking beam 35. Obviously, by reason of this particular character of connection between the walking 110 beam and the Samson post there is provided an underslung connection permitting the walking beam to operate properly under unusual strain. The forward end of the walking beam 35 is equipped for receiving the 115 usual depending temper screw 36 and at its rear end the usual depending shaft pitman 37. Secured at its lower end to the mast supporting bar 8 of the rig bed frame intermediate the standards of the Samson post 30 120 is a vertically extending and slightly forwardly projecting post 38, the upper end of which terminates considerably beneath the upper end of the Samson post and that is also braced at its upper end to the Samson 125 post as indicated by the reference character 39. The length of this post 38 is such that under the normal movement of the walking beam 38 the forward end thereof will not encounter said post. However, in the event 130

the pitman 37 should become disconnected from the walking beam or from the power shaft, hereinafter described, the walking beam will strike against the post 38 for limiting the downward swinging movement thereof, which frequently results in injury to the workmen.

Secured to adjacent longitudinal bed frame bars 5 and 6 at one side of the frame and considerably in back of the mast structure 10 is a pair of vertically extending shaft supporting posts 40—40 suitably braced to the frame and upon the upper end of which is journaled a power shaft 41. At the inner side of the outermost shaft post 40 said shaft 41 has keyed thereto a belt receiving rotary pull wheel 42 over which is to be extended a rearwardly directed endless belt 43 that is in turn trained over a pulley upon the power shaft 41 of a suitable source of supply, not disclosed.

Arranged upon the inner end of this shaft 41 which projects inwardly of the innermost shaft post 40 is a crank arm 43' equipped at its free end with a horizontal pin 44 for attachment to the walking beam pitman 37 or for receiving a cable pulley 45, as disclosed in Figures 3 and 1, respectively.

Arranged upon the outer longitudinal frame bar 5 of the bed frame in back of the rotary bull wheel 42 is a vertically extending bracket 46, see Figure 5 to which is pivotally secured a vertically extending lever 47. Arranged for rotation within a socket formed at the inner side and adjacent the lower end of this lever 47 is one end of an inwardly extending transverse shaft 48, the inner end of which is suitably journaled upon the upper end of a standard 49 arranged upon the foremost central longitudinal bar 6 of the bed frame of the rig as clearly disclosed in the top plan view of Figure 8. The bearing for this end of the shaft is preferably longitudinally and vertically adjustable so that the shaft may be properly centered with respect to the attaching point between the outer end of the shaft and the vertical lever 47. This shaft 48 has keyed thereto a double cable drum 50 of generally conventional construction and upon which is wound a cable 51, which is adapted to be wound upon and released from the inner drum section, as in Figure 8. The inner end of this double drum terminates considerably inwardly of the rotary bull wheel 42 for a purpose presently to be described.

Adjacent the point of attachment of the outer end of the shaft 48 with respect to the vertical lever 47 said shaft is equipped with a friction wheel 52 directly in alignment with the bull wheel 42 and adapted to have frictional engagement therewith when the lever 42 is swung in a forward direction, with the obvious result that rotation is imparted to the shaft 48 for winding the cable 51 thereon. From the drum 50 this cable 51 extends

upwardly and is trained over the pulley 21 arranged beneath the uppermost pulley 20 of the mast construction 10. Arranged upon the free end of this cable 51 is a conventional bailer bucket 53 that is to be raised and lowered into the well by the forced rotation of the drum carrying shaft 48 or the releasing of the shaft, respectively. Obviously, the movement of the friction wheel 52 from the surface of the bull wheel 42 after the bailer 75 has been raised will permit the same to drop into the well under its own weight. In order to break the descent of the bailer bucket when the shaft 48 is released, there is arranged in back of the friction wheel 52 upon the adjacent outer longitudinal bed frame bar, a post 54, the edge adjacent the friction wheel 52 being curved and having a braking face 55 thereon. Obviously by moving the lever 47 rearwardly with respect to the bull wheel 42, 80 said friction wheel 52 will be moved against the braking face 55 for stopping the rotation of said shaft 48. The relative position of the bull wheel and post 54 at opposite sides of the friction wheel 52 is such that the wheel 90 may be maintained out of contact with the post and bull wheel to permit of the free movement of the shaft 48 during the dropping of the bailer bucket.

Any means may be provided whereby the lever 47 may be operated, this means preferably consisting of a bar 56 that extends forwardly and downwardly at the outer side of the bull wheel 42, and that is pivotally connected at one end to the lever 47 and at its opposite end to a crank 57 upon one end of a transversely extending rock shaft 58, see Figure 5, that is suitably mounted upon the mast supporting bar 8 and that is equipped at its inner end with a handle 59. Mounted 100 upon vertical jack posts 61—61 at the rear ends of the outermost longitudinal frame bars 5—5 are the opposite ends of a transversely extending shaft 62. This shaft 62 is equipped with a relatively large double cable 105 drum 63, the innermost end of which is directly in back of the center of the bailer cable drum 50, as clearly disclosed in Figure 8. Wound upon this drum 63 is a cable 64 that extends upwardly from the innermost drum 110 section and that is trained over the uppermost pulley 20 of the mast construction 10 from where the same extends downwardly and has attached to its free end a suitable drilling tool 65. Obviously when the bailer 115 53 is being operated, this tool is extended out of the path of movement of the bailer, and so held in any suitable manner, and by the same token the bailer 53 is extended out of position above the well during the operation 120 of the drill tool 65.

In spaced relation with the inner end of the drum 63, the shaft 62 has keyed thereto a relatively large pulley wheel 66, the face 130 of which is formed with a pair of circum-

ferential channels, preferably of V-shape in cross section similar to the channels disclosed in one of the elements shown in Figure 13. Arranged upon the inner face of the rotary bull wheel 42 and of smaller diameter than the pulley wheel 66 is a ring 67 of general L-shape in cross section as disclosed in Figures 12 and 13. The vertical wall of this ring is bolted or otherwise rigidly secured to the inner face of the rotating bull wheel 42, while the horizontal wall thereof is formed at equally spaced points with circumferential slots 68 preferably four in number. Arranged for free turning movement upon the horizontal wall of the ring 67 is a collar 69 that is formed with a pair of circumferentially extending channels 70 of V-shape in cross section, as clearly disclosed in Figure 13. Loosely mounted upon the power shaft 41 to which the bull wheel 42 is keyed is the hub 71 of a generally similar wheel-like unit 72 that includes a circular rim portion 73 arranged beneath and in concentric relation with the horizontal wall of the bull wheel 42 attached ring 67. The outer edges of the collar 69 and the rim portion of the wheel 72 are interconnected by a flat ring 74, see Figures 11 and 13.

Arranged for radial movement between the horizontal wall of the ring 67 and the rim portion 73 of the ring-like unit 72 and beneath the circumferential slot 68 in said horizontal ring wall are brake shoes 75 formed intermediate their ends with radially inwardly extending cups 76 that have sliding movement within the outer end of cylinders 77 arranged at their outer ends within openings in the rim 73 of said wheel-like unit 72, see Figures 11 and 13. Movable through each cylinder 77 and slideable through the outer end wall thereof as well as through the adjacent wall of the cup 76 of the complementary brake shoe 75 is a pin 78. A head 79 is equipped on the outer end of the pin 78 and is operable within the cup 76. This head is adapted to engage within the adjacent slot of the ring 67 when projected into the position indicated in Figures 11 and 13. Surrounding each pin 78 within its cylinder 77 is an expansible coil spring 80, the purpose of which is to normally exert an outward pressure against the cup of the respective shoe 75 for causing frictional engagement of the same with the horizontal wall of the ring 67 for thereby locking the ring to the wheel-like unit 72 that is connected with the pulley collar 69.

The inner end of each pin 78 beyond the cylinder 77 carries a head 81, while to these various heads are pivotally connected the outer ends of radiating arms 82 the inner ends of which are pivotally connected to a clutch throw collar 83 slideable upon the hub portion 71 of the wheel-like unit 72. Operatively associated with this collar 83 is the

upper yoked end of a lever 84 which is pivoted in spaced relation with the inner side of the adjacent power shaft jack-post 40 through the instrumentality of a horizontal bracket 85. Pivoted to the lower end of this lever is an inwardly extending link member 86 that is in turn pivotally connected at its inner end to a bell crank 87 that is pivoted as at 89 to the adjacent central longitudinal frame bar 6. Pivoted to the outer end of the bell crank 87 is the inner end of a control rod 90 that extends rearwardly of the rig and that is pivoted at its outer end to the lower end of a hand lever 91 that is pivoted adjacent its lower end to a bracket 92 arranged upon the adjacent central longitudinal frame bar, see Figure 8.

Trained around the pulley wheel 66 of the drum shaft 62 and the collar 69 of the clutch unit is a pair of endless V-type belts 93-93 that obviously work in the circumferential channels of said wheel and said collar. From a careful consideration of Figure 13 it will be readily understood that the inward movement of the collar 83 will cause the outward movement of the pins 78 which will release the pressure of the heads 79 of said pins from the bottom walls of the shoe cups 76 whereupon the springs 80 will exert their force to frictionally engage the shoes 75 with the horizontal wall of the ring 67, thus providing a friction clutch between the bull wheel and said collar 69. As soon as the circumferential slots 68 of said ring 67 move into the path of the head 79 of said pins, the heads will engage within said slots for causing a positive lock between the bull wheel and said collar.

The power rotation of the double cable drum 63 will cause the winding of the cable 64 thereon with the obvious result of raising the drill tool 65. As soon as the clutch is released, the tool drops under its own weight which is a generally conventional drilling action.

Within the shaft post 61 the end of the shaft 62 opposite from that equipped with the belt pulley 66 is equipped with a friction wheel 94 over which is arranged a metallic brake band 95, one end of which is anchored to the adjacent bed frame 5 as clearly disclosed in Figure 1. The opposite end of this band is connected in a conventional manner to a stub crank shaft 96, the outer end of which is equipped with a crank 97 to which is pivoted one end of a rod 98 that extends forwardly and that is operatively connected to the lower end of a throw lever 99 pivotally attached adjacent its lower end with the upper end of a suitable standard 100 that is arranged upon the adjacent outer longitudinal bed frame 5.

Suitably journaled upon the upper ends of short shaft posts 101-101 between the mast construction 10 and the rotary bull wheel 42 is a transverse shaft 102 that is

equipped at the inner side of the bull wheel 42 with a double cable drum 103 upon which is wound a length of cable 104, which cable extends upwardly and is guided over a small 5 pulley 105 associated with the back side and lower end of the adjacent sheave carrier 24 pivoted within the upper end of the mast construction 10. The cable 104 is thence so engaged around the pulleys of the sheave carrier 24 and the pulleys of a block 106 as to provide a block and tackle arrangement whereby well casing sections may be raised or lowered from or into the well. During use 10 of the block and tackle arrangement the drill tool and bailer bucket are disposed out of the path of movement of the block while the pivotal sheave carriers 24-24 are swung outwardly so that the block of the block and tackle will be centered directly above the 15 well. At the inner end of this drum shaft 102 the same is equipped with a sprocket gear 107 over which is trained a rearwardly and upwardly extending sprocket chain 108 and that is in turn trained over a sprocket gear 109 20 carried by a clutch collar movable upon the shaft 41 and is complementary to another rigidly mounted clutch collar upon said shaft with the obvious result that when the sliding collar is moved into engagement with the 25 rigid collar, rotation will be imparted to the drum 103 for winding the cable thereon for raising the block 106. The releasing of the collar will permit the block to drop of its own weight, while the rotation of the drum 30 shaft may be checked during the downward movement of the block by suitable band brakes designated generally by the reference character 110, the band of which is operable from the adjacent side of the machine by a 35 lever 111 that may be maintained in braking position by suitable fastener 112 arranged on the outer side of the adjacent bed frame bar 5.

Obviously, after the spudding in operation has been performed, the drill tool cable 44 45 is attached to the temper screw 36 so that the deep drilling operation may be performed in a generally conventional manner.

It will thus be seen that I have provided a highly novel, simple and extremely useful 50 well drilling rig that is well adapted for all

the purposes heretofore designated, and even though I have herein shown and described the invention as consisting of certain detail structural elements it is nevertheless to be understood that some changes may be made 55 therein without affecting the spirit and scope of the appended claims.

Having thus described the invention, what I claim as new is:—

1. In a well drilling rig, a bed frame, a vertical mast structure secured at its lower end to the frame, a series of independently operable cable drums disposed upon the frame in back of the mast, cables arranged upon said drums and adapted to be extended through 60 the mast at the upper end thereof, a pair of vertically arranged transversely spaced units pivotally arranged at their lower ends within the mast, sheaves arranged within the units, the cable from one of the drums adapted to 65 be so guided over the sheaves as to provide a tackle structure, a pulley block unit arranged upon the various runs of the tackle, and means whereby the various drums may be rotated in a certain direction for winding 70 the cables thereon.

2. In a well drilling rig, a bed frame, a vertical mast structure secured at its lower end to the frame, a series of cable drums disposed upon the frame in back of the mast, 80 cables arranged upon said drums and adapted to be extended and guided through the upper end of the mast, a pair of vertically extended units arranged in transverse spaced relation with the upper end of the mast, cable 85 guide sheaves arranged in said unit and over which the cable of one of the drums is to be extended for providing a tackle unit of a block and tackle structure, a pulley block suspended from and operable by the runs of 90 the tackle, a pivotal connection between the lower ends of the sheave units and the mast structure whereby the upper sheave carrying ends thereof may be extended outwardly of the mast for disposing the pulley block centrally of the well, and means whereby the cable drums may be rotated for winding the 95 cables thereon.

In testimony whereof I affix my signature.

EDWIN O. ADAMS.
